UNITED STATES PATENT OFFICE.

JAMES H. COFFMAN, OF COLUMBUS, OHIO.

DESIGN FOR A VENEER-PRESSING MEMBER.

SPECIFICATION forming part of Design No. 34,182, dated March 5, 1901.

Application filed February 9, 1901. Serial No. 46,749. Term of patent 14 years.

To all whom it may concern:

Be it known that I, JAMES H. COFFMAN, a citizen of the United States of America, residing at Columbus, in the county of Franklin and State of Ohio, have invented and produced a certain new, useful, and original Design for an Article of Manufacture—to wit, a Veneer-Pressing Member—of which the following is a specification, reference being had to the accompanying drawings, forming a part thereof.

In said drawings, Figure 1 is a side view of a veneer-pressing member embodying my design. Fig. 2 is a plan view of the same. Fig. 3 is a longitudinal vertical section of the same, taken on line 3 3 in Fig. 2, these three views being deemed necessary for full illustration.

The leading and essential feature of my design for a veneer-pressing member consists of the peculiar and novel lower-surface formation of the same between a curved line 2 2 and the straight line 6 6, which may be described as follows: From side to side of the lower surface, between points 2 2 in either edge, it will be supposed a line extends in the nature of an arc of a circle and crosses section-line 3 3 at 7. Starting at 2 and proceeding down one edge, the design moves in an irregular curve to 4, and from 4 to 5 on a very slight com-

pound curve, and then downward from 5 to 6 on an irregular curve. If section-lines parallel with line 3 3 were taken at intervals through the portion between the supposed arc 3 7 3 and the straight-line connecting-points 4 4, it would be seen that each proceeded on an irregular curve, but that each curve would diminish as the said section-line neared either outer edge.

The several minor features of my design for a veneer-pressing member may be stated as follows: The lower surface, between the supposed arc 2 7 2 and the edge, is curved up and out from said imaginary arc to the edge. The remainder of the lower surface is flat. Each side is flat, and the same are parallel. So also are the ends, while the top is flat and stands at right angles to the sides and ends.

Having thus described my design, what I claim is—

The design for a veneer-pressing member substantially as shown and described.

Signed by me at Pittsburg, Pennsylvania, this 17th day of November, A. D. 1900.

JAMES H. COFFMAN.
